US0D1091986S

(12) **United States Design Patent** (10) **Patent No.:** **US D1,091,986 S**
(45) **Date of Patent:** **** Sep. 2, 2025**

(54) **HANDHELD VACUUM**

(71) Applicant: **HaoXiang Xue**, Guangdong (CN)

(72) Inventor: **HaoXiang Xue**, Guangdong (CN)

(**) Term: **15 Years**

(21) Appl. No.: **29/924,419**

(22) Filed: **Jan. 18, 2024**

(51) **LOC (15) Cl.** **15-05**

(52) **U.S. Cl.**

USPC **D32/18**

(57) **CLAIM**

The ornamental design for a handheld vacuum as shown and described.

DESCRIPTION

FIG. 1 is a perspective view of a handheld vacuum showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof; and,

FIG. 9 is a perspective view of a handheld vacuum expanded state showing my new design.

The broken lines depict portions of the handheld vacuum and form no part of the claimed design.

1 Claim, 9 Drawing Sheets
